UNITED STATES PATENT OFFICE.

JOHN HANDSLEY DALES, OF LEEDS, COUNTY OF YORK, ENGLAND,
ASSIGNOR TO GEORGE DALTON, OF SAME PLACE.

STEAM-ENGINE.

SPECIFICATION forming part of Letters Patent No. 423,742, dated March 18, 1890.

Application filed September 19, 1889. Serial No. 324,385. (No model.) Patented in England October 3, 1888, No. 14,216.

To all whom it may concern:

Be it known that I, JOHN HANDSLEY DALES, civil engineer, a subject of the Queen of Great Britain, residing lately at 37 Hanover Street, 5 Leeds, but now at 45 Lofthouse Place, Leeds, in the county of York, England, have invented certain new and useful Improvements in Steam-Engines, (for which I have obtained a patent in Great Britain, No. 14,216, bearing 10 date October 3, 1888,) of which the following is a specification.

This invention relates to steam-engines provided with centrifugal governors; and it consists in the construction and combinations of 15 devices hereinafter described and claimed.

My invention is specially but not exclusively applicable to governors of the right-angled lever-arm spring-load type.

In order that my said invention may be 20 particularly described and ascertained, reference is hereby made to the accompanying drawings, in which similar letters of reference indicate corresponding parts.

Figure 1 is a side elevation, and Fig. 2 an 25 end elevation, illustrating the application of my improvements to the description of centrifugal governor above more especially referred to. Fig. 3 is an enlarged horizontal view (partly in section) of the portion of the 30 upper part of the revolving head. Fig. 4 is an end view of the valve-chest fitted to the power-cylinder O; and Figs. 5 and 6 are respectively vertical and horizontal sections of the same valve-chest, valve, and ports.

35 A is the head or bracket casting, the arms F F being formed in one therewith. These arms carry the governor-arm centers B, which are fitted with balls or rollers C C, as shown. The head-casting also forms a bearing for the 40 load-spring A'. The anti-friction balls C are fitted in suitable recesses formed in the boss of the right-angled lever-arm D in such a manner that the balls roll between conical bearings in the adjusting-bosses E, which are 45 carried by the bracket-arms F, the cones being capable of adjustment for the purpose of taking up any slackness in the bearings. A pin or bolt G passes through and in contact with the adjusting-bearings, but clear of the hole 50 through the governor-arm boss, for the pur-

pose of holding the bosses in adjustment. The horizontal arms D' of the governor are fitted radially to the spindle, and are connected to the slider H by means of short links I I, which are also fitted with adjustable ball-bearings. The slider H is provided with a collar J, which by means of pins working in slots engages with a forked lever K, which is keyed to a rocking shaft L. This shaft L is carried in ball-bearings on the upper ends of 55 the piston-rods M and N, M being the piston-rod of the power-cylinder O, and N being the piston-rod of the cataract-cylinder P. The pistons of these cylinders are fitted with through piston-rods and stuffing-boxes at 60 each end, and the lower ends of the piston-rods M N are attached to the cross-head W, the latter being fitted with a slipper or other guide. The rocking shaft L is provided also with a lever Q, which is connected by 70 means of a rod R with a lever S, which rocks a spindle T and a small inside lever U, which actuates a piston or slide valve V, (not necessarily of the type shown,) which in performing its functions admits or exhausts 75 steam to either the top or bottom end of the auxiliary power-cylinder O, as may be required by the gear. The cataract-cylinder P is entirely filled with liquid (preferably oil) and hermetically sealed as far as is practicable, 80 and in performing its functions the cataract-piston forces the liquid to circulate through the passage P' (shown by dotted lines in Fig. 2) or through a passage in the piston itself. 85

The power and motion of the auxiliary power-cylinder O are transmitted by means of the sliding cross-head W, links X X, and bell-crank levers X' and Y, or other suitable gear, to the expansion-valve, throttle-valve, or 90 other gear of the engine to be controlled. Preferably I use an expansion-valve worked and varied in the cut-off by a slot-link die and two eccentric-rods, the slot-link being controlled and held in position by suitable 95 connections with the cross-head W or the bell-crank levers X' and Y, or either of them.

Fig. 3 shows a portion of the upper end of the head-casting A with one pair of arms F F, also a horizontal arm D' of the governor 100

in position between the arms F F; also, the method of placing the anti-friction balls C C in the recess of the governor-arm D by means of the adjusting-bosses E and the pin or bolt 5 G; also, the method of attachment of the links I I as well to the forked end of the governor-arm as to the studs H' of the slider H, and the method of fitting the anti-friction balls C in the bearings and adjusting them 10 by means of the nuts H².

Referring to Figs. 4, 5, and 6, V is the valve, consisting of two solid pistons c c, united together by cross-webs, as shown. a is the steam-induction port. b is the eduction-15 port. d d are two ports leading to the cylinder O. The piston-valve is formed without lap. S is the horizontal lever, T the spindle, and U the inside lever working in a slot in the valve-rod. The action of this arrangement of the invention may be described as follows: When the governor-arms D D are thrown outward beyond the position shown in Fig. 1, the slider H is lifted, and also the levers K and Q and the link R, by the rock-20 ing of the shaft L. This action moves the lever S of the piston-valve V, and by thus admitting steam into, say, the upper end of the power-cylinder O the piston is caused to move downward. In so doing the piston brings 25 down also the levers and other parts which were first lifted by the governor, and the consequence is, that the ports of the valve V, which have been opened by the governor, are closed by the subsequent action of the piston, 30 the steam-supply is stopped, and the piston remains in a position corresponding but opposite to that of the slider H. If the auxiliary piston happens to overact, such overaction, by moving the valve beyond the position 35 of closed ports, opens to the exhaust that end of the cylinder which contains the excess of pressure, and thus exactly adjusts the relative positions of the slider and the power-piston. Any tendency toward a jerky action 40 of the parts is counteracted by the cataract-cylinder.

My improved adjustable roller-bearings may be applied to many other forms of governors, as well as that above described, with or without 45 a power-cylinder, and also with or without a cataract-cylinder.

I claim—

1. In a steam-engine governor, the combination of the bracket-arms F, the adjustable bosses E, supported in said brackets and provided with conical bearings, the oscillating governor arms or levers D D', having recessed centers B, the anti-friction balls or rollers C, located between said centers and conical bearings, the slider H, having a link-connection 55 with the governor-arms, the rock-shaft L, having a lever-connection with the slider, and the valve and its connections, substantially as described.

2. In a steam-engine governor, the combination of the cylinders O P, the piston-rods M N, the shaft L, connected with said rods and provided with anti-friction ball-bearings, the slider H, the lever-connection K between said shaft and slider, and the oscillating governor arms or levers D D', supported in anti-friction ball-bearings and having a link-connection 60 I with the slider, substantially as described.

3. In a steam-engine governor, the combination of the power-cylinder O, the cataract-cylinder P, the valve V, the piston-rods M N, the rock-shaft L, connected with said rods and provided with anti-friction bearings, the slider H, the lever-connection K between said shaft 70 and slider, the lever Q, mounted on the rock-shaft L, and the rod R, lever S, spindle T, and lever U, whereby the rock-shaft and valve are connected, substantially as described.

4. The combination of the bracket-arms F, 75 the oscillating right-angled governor arms or levers D D', the balls or rollers C, supporting the oscillating arms or levers, the spindle to which the said arms or levers are connected, the slider H, the rock-shaft L, having a lever-connection K with the slider, the power-cylinder 80 O, the cataract-cylinder P, and the piston-rods M N, connected with the rock-shaft, 85 substantially as described.

JOHN HANDSLEY DALES.
